US00D951017S

(12) **United States Design Patent** (10) **Patent No.:** **US D951,017 S**
Lira-Nunez et al. (45) **Date of Patent:** **** May 10, 2022**

(54) **GRILL SHROUD**

(71) Applicant: **Weber-Stephen Products LLC**,
Palatine, IL (US)

(72) Inventors: **Carmen O. Lira-Nunez**, Downers
Grove, IL (US); **Mark Richard Pavel**,
Lisle, IL (US); **Anton Kalisiak**,
Palatine, IL (US)

(73) Assignee: **WEBER-STEPHEN PRODUCTS
LLC**, Palatine, IL (US)

(**) Term: **15 Years**

(21) Appl. No.: **29/773,421**

(22) Filed: **Mar. 9, 2021**

Related U.S. Application Data

(60) Continuation of application No. 29/723,201, filed on
Feb. 5, 2020, now Pat. No. Des. 915,140, which is a
division of application No. 29/619,290, filed on Sep.
28, 2017, now Pat. No. Des. 877,564.

(57) **CLAIM**

The ornamental design for a grill shroud, as shown and described.

DESCRIPTION

FIG. 1 is a perspective view of a grill shroud of the present invention.

FIG. 2 is a top view of the grill shroud of the present invention.

FIG. 3 is a front view of the grill shroud of the present invention.

FIG. 4 is a left side view of the grill shroud of the present invention, the right side view being a mirror image of the left side view; and,

FIG. 5 is a back view of the grill shroud of the present invention.

The broken lines showing portions of the article form no part of the claimed design.

1 Claim, 5 Drawing Sheets
